NAIL HOLDER

Louis A. McClung, Denver, Colo.

Application December 15, 1950, Serial No. 200,924

3 Claims. (Cl. 145—30)

1

This invention relates to a nail holder or clamp for attachment to a hammer.

An object of this invention is to provide a nail holder or clamp for attachment to a hammer which is adapted to hold a nail in a driving position wherein the nail can be started into the work by a blow of the hammer, after which the nail may be released from the holder or clamp and driven into the work in the usual manner.

Another object of this invention is to provide a nail holder or clamp which can be readily attached to any type of hammer and cooperates therewith for supporting the nail to be driven into a piece of work.

A further object of this invention is to provide a nail holder for attachment to a hammer which facilitates the driving of nails into inaccessible places wherein it is ordinarily impossible to hold the nail by hand in position to be driven into the work by the hammer.

A still further object of this invention is to provide a nail holder for attachment to a hammer which makes it possible for a carpenter to start and drive a nail into a piece of work while in an unhandy or precarious position having only one hand free.

A still further object of this invention is to provide a nail holder or clamp for attachment to a hammer which is relatively simple in structure and cheap to manufacture.

The above and still further objects and advantages of the present invention will become apparent upon consideration of the following detailed description of the invention when taken in conjunction with the accompanying drawings, wherein:

Figure 1 is a side elevational view of the nail holder or clamp of the present invention, shown attached to a plane surface of a hammer head and in a nail receiving position;

Figure 2 is a side elevational view of the nail holder and hammer shown in Figure 1 with the holder in a nail supporting position;

Figure 3 is an enlarged fragmentary sectional view taken along the line 3—3 of Figure 2; and,

Figure 4 is an enlarged exploded perspective view of the nail holder or clamp of the present invention.

Referring now with particularity to the drawings, wherein like reference numerals have been used throughout the several views to designate like parts, there is shown the nail holder or clamp of the present invention, generally designated by the reference numeral 10 which is supported on a hammer 11 including a handle 12, and a hammer head 13 having at least one plane surface 14.

The holder or clamp 10 includes a base plate 15 which is fabricated of a resilient material and is normally arranged in a nail supporting position illustrated in Figure 2 in abutting and confront-

2

ing relation with respect to the plane surface 14 of the hammer head 13. The base plate 15 is provided with a longitudinal slot 16 which extends inwardly from one end thereof and terminates contiguous to and spaced from the other end thereof. The resilience of the base plate 15 and the size of the slot 16 are selected so that nails of various sizes can be embracingly received and gripped within the slot 16. The base plate 15 is preferably fabricated of a springy metal which is durable enough to withstand long hard use without breaking. The base plate 15 is further provided with a transversely extending bolt receiving aperture 17 which is spaced from the terminating end of the slot 16.

Extending through the bolt receiving aperture 17 of the base plate 15 is a bolt 20 which is rotatably supported within the hammer head 13 and mounts the base plate 15 for movement from the nail supporting position illustrated in Figure 2 to the nail receiving position illustrated in Figure 1 with the open end of the slot 16 projecting beyond the plane surface 14 for the insertion therethrough of a nail to be driven into the piece of work. The bolt 20 includes a threaded shank 21 which is received within an oppositely threaded bore 22 provided in the plane surface 14 of the hammer head 13 and a multi-sided head 23 arranged exteriorly of the base plate 15.

Operatively connected to the assembly of the base plate 15 and the bolt 20 is a catch and lock element 25 which non-rotatably secures the assembly of the bolt 20 and the base plate 15 together and engages within a depression 26 provided in the plane surface 14 for holding the base plate 15 in the nail supporting position illustrated in Figure 2. As clearly shown in Figure 3 the base plate and the plane surface 14 of the hammer head 13 cooperate in the nail supporting position of the base plate to support a nail in a driving position with the head thereof disposed intermediate the abutting and confronting surfaces of the hammer head 13 and the base plate 15. The catch and lock element 25 is fabricated of a resilient material and includes an elongated body 27 having an end portion in the form of a circular lock washer 28 provided with a centrally disposed aperture 29 for the extension therethrough of the shank 21 of the bolt 20. The lock washer 28 is adapted to be arranged between the head 23 of the bolt 20 and the portions of the base plate 15 bounding the bolt receiving aperture 17 and is formed contiguous to the adjacent end of the body 27 with an abutment 30 which bears against one side of the multi-sided head 23 for holding the bolt 20 against rotation with respect to the catch and lock element 25. The other end portion of the body 27 is formed with an elongated arm 31 which is adapted to overlie a portion of the slot 16 contiguous to the termi-

nating end thereof. Secured to or formed integrally with the arm 34 is a depending ear 32 which extends transversely through the slot 16 contiguous to and spaced from the open end thereof and is engageable within the depression 26 for holding the base plate 15 in the nail supporting position illustrated in Figure 2.

For actually mounting the nail holder on the hammer head 13 any plane surface of the hammer is selected and provided with a threaded bore 22 for the reception of the threaded shank 21 of the bolt 20. The bolt 20 is then tightened down until the base plate 15 is arranged in confronting and abutting relation with respect to the plane surface 14 with the catch and lock element 25 interposed between the head 23 of the bolt and the exterior surface of the base plate 15. It is to be noted that the length of the depending catch or ear 32 is selected so that the free end thereof will engage within the depression 26 when the base plate 15 is in the nail holding or supporting position illustrated in Figure 2.

In actual use, the assembly of the bolt 20, the base plate 15 and the catch and lock element 25, are rotated to the nail receiving position illustrated in Figure 1. The nail is then inserted within the open end of the slot 16 with the nail head interposed between the abutting and confronting surfaces of the base plate 15 and the plane surface 14 of the hammer head 13. The assembly is then rotated to the nail supporting position illustrated in Figure 2 and held therein by the depending ear or catch 32 which engages within the depression 26. The resilience of the catch and lock element 25 assures the maintenance of the catch within the depression 26 yet permits the assembly of the base plate, bolt and the catch and lock element to be rotated to the position illustrated in Figure 1. Upon swing the hammer, a nail can be started into the work after the nail can be released from the holder.

Although one embodiment of the nail holder or clamp of the present invention has been described, it is readily apparent that numerous modifications can be made without departing from the spirit of the invention as set forth in the appended claims.

What I claim is:

1. A nail holder for attachment to a hammer head including a plane surface comprising a base plate fabricated of resilient material arranged in a nail supporting position in abutting and confronting relation with respect to said plane surface, said base plate being provided with a longitudinally extending slot having an open end for embracingly receiving a nail, bolt means extending transversely through said base plate and rotatably supported in said hammer head for mounting said base plate for movement from said nail supporting position to a nail receiving position with the open end of the slot projecting beyond said plane surface for the insertion therethrough of the nail, and a catch and lock means operatively connected to the assembly of said base plate and bolt for non-rotatably securing said assembly together and engageable within a depression provided in said plane surface for holding said base plate in said nail supporting position wherein said plane surface and base plate cooperate to support the nail in a driving position, said catch and lock means including an elongated body having one end formed into a depending ear extending transversely through said slot contiguous to and spaced from the open end thereof.

2. A nail holder for attachment to a hammer head including a plane surface comprising a base plate fabricated of resilient material arranged in a nail supporting position in abutting and confronting relation with respect to said plane surface, said base plate being provided with a longitudinally extending slot having an open end for embracingly receiving a nail, bolt means including a multi-sided head extending transversely through said base plate and rotatably supported in said hammer head for mounting said base plate for movement from said nail supporting position to a nail receiving position with the open end of the slot projecting beyond said plane surface for the insertion therethrough of the nail, and a catch and lock means operatively connected to the assembly of said base plate and bolt for non-rotatably securing said assembly together and engageable within a depression provided in said plane surface for holding said base plate in said nail supporting position wherein said plane surface and base plate cooperate to support the nail in a driving position, said catch and lock means including an elongated body having one end formed into an abutment bearing against one side of said multi-sided head.

3. A nail holder for attachment to a hammer head including a plane surface comprising a base plate fabricated of resilient material arranged in a nail supporting position in abutting and confronting relation with respect to said plane surface, said base plate being provided with a longitudinally extending slot having an open end for embracingly receiving a nail, bolt means including a multi-sided head extending transversely through said base plate and rotatably supported in said hammer head for mounting said base plate for movement from said nail supporting position to a nail receiving position with the open end of the slot projecting beyond said plane surface for the insertion therethrough of the nail, and a catch and lock means operatively connected to the assembly of said base plate and bolt for non-rotatably securing said assembly together and engageable within a depression provided in said plane surface for holding said base plate in said nail supporting position wherein said plane surface and base plate cooperate to support the nail in a driving position, said catch and lock means including an elongated body having one end formed into an abutment bearing against one side of said multi-sided head, the other end of said body being formed into a depending ear extending transversely through said slot contiguous to and spaced from one end thereof and selectively engageable within said depression.
